CALCULATING MACHINE

Robert L. Muller, Detroit, Mich., assignor to Burroughs Adding Machine Company, Detroit, Mich., a corporation of Michigan

Application June 1, 1937, Serial No. 145,713
Renewed May 28, 1938

26 Claims. (Cl. 197—128)

This invention relates to an accounting machine and is directed more particularly to the paper handling equipment of such a machine.

In certain classes of accounting work, it is desirable to print a running record or journal sheet which remains in the machine and contains all the entries that are made on separate sheets such as work sheets or ledger sheets which are inserted and removed from in front of the platen.

10 Machines equipped to handle paper in this manner are generally termed front-feed machines.

The present invention is particularly applicable to this type of machine and it concerns an improvement for speeding up operation of the machine by providing for automatic printing of the total at the bottom of the sheet regardless of the number of entries preceding the total and for automatic removal of the work sheets while the record sheet remains in the machine, that is, 20 the operator need pay little attention to the handling of the paper and can direct most of his attention to making the entries.

The general object of this invention is to provide an improved paper handling equipment for 25 accounting machines.

A further object is to provide an automatic paper spacing mechanism.

A more specific object is to provide an improved sheet ejecting means for ejecting work sheets 30 from a front-feed type of machine.

Other and more particular objects are to provide a simply constructed mechanism of the character that will be automatic, that will stack the work sheets in proper order, that will perform 35 many of its operations automatically so as to speed up operation of the machine, and that will be easy to operate, readily accessible and fool-proof against misoperation.

Other objects and advantages of the invention 40 will appear from the following specification and drawings.

An embodiment of this invention is shown in the accompanying drawings, in which:

Figure 1 is a right side elevation of a portion 45 of a "Burroughs" machine having the present invention incorporated therein and illustrating the platen in printing position;

Fig. 2 is a fragmentary detail of the paper ejecting means and illustrating the parts in printing position;

Fig. 3 is a right side elevation of the rear portion of the machine illustrating the parts in open throat and paper ejecting positions;

Fig. 4 is a left side elevation of the rear portion 55 of the machine showing the line spacing mecha-

nism for listing and totaling operations and with a work sheet in printing position and the part in position immediately after a first item entering operation which closes the throat and moves the platen to printing position;

5

Fig. 5 is a view similar to Fig. 4, illustrating a portion of the mechanism of Fig. 4 in position after three items have been entered and the total key depressed and positioned to cause the platen to be line spaced to print the total at the bottom 10 of the work sheet; and

Fig. 6 illustrates samples of work performed by the machine and shows both bill forms or work sheets together with a carbon copy record strip.

The invention is shown applied to a "Burroughs" high keyboard type of bookkeeping or accounting machine that is well known so that a detailed description of it is not necessary. It will be understood that the invention can also be applied to other types of machines and that the disclosure herein is by way of illustration.

General machine features

Referring to Fig. 1 the machine has a plurality of amount keys 9 upon which items may be entered, after which the machine can be operated by depressing a motor bar 10 that causes the motor 11 to oscillate the main shaft 12 to give the machine a cycle of operation, said cycle, in the machine shown, including a forward and a return 30 stroke. During its operating cycle the machine performs certain calculating functions, such as addition, subtraction or totaling, the latter by use of a total key 13. The machine may be controlled and operated to cause it to perform other functions such as disclosed on the "Burroughs" machines now on the market and in many patents on said machines.

A printing mechanism is provided, of which a portion is shown at 14, said mechanism being 40 normally operated near the end of a forward stroke of the machine and serving to print the amount of the items entered or of the calculations performed.

In the illustrated machine, no provision is made 45 for printing automatically in different columns of the paper inserted in the machine. Instead, the machine is provided with a non-traveling or stationary carriage having a platen P which may be line spaced after each printing operation by a 50 line spacing mechanism of which a portion 18 is shown in Figure 1. This mechanism can be adjusted to line space the platen or it may be line spaced at the end of a particular operation. It 55 will be understood that if a traveling paper car-

riage is desired one may be employed as illustrated in the Rinsche Patent No. 1,580,534.

Platen mounting

5 The platen P is fixed to a shaft 20 journaled to rotate in two spaced side plates 21 in Figs. 1 and 4 which are pivoted to a shaft 22 carried by the main frame of the machine. The platen is thus supported in a rockable frame on the machine proper and may be moved from printing to an out-of-printing or front-feed position. For this purpose one side plate 21 is extended downwardly and carries a stud 23 which engages the cam slot 24 formed in one arm 25 of a bell 10 crank pivoted at 26 and having a second downwardly projecting arm 27 terminating in a lug 28. A spring 29 secured to the machine frame and to arm 25 tends to rotate the crank counterclockwise (Figs. 1 and 3) to move the platen to front-feed position. The crank however is latched against rotation by a latch 31 pivoted on shaft 32 and urged clockwise by a spring 33. This latch has a hooked end 34 which engages lug 28 15 to retain the arm 27 in its clockwise position 20 and is under control of the total key 13, as will later be explained.

The platen is returned to printing position through the medium of a link 36 pivotally connected at one end to the lower portion of arm 25 30 and at its other end to the rear end of a lever 37 pivoted intermediate its ends upon shaft 38. The forward end of lever 37 carries a pass-by pawl 39 which is adapted to be engaged by a cam 40 carried by the main shaft 12 of the machine 35 which shaft is oscillated at each cycle of machine operation. It will be seen from Figs. 1 and 3, that when the platen is in printing position, the pass-by pawl 39 is out of the path of the cam 40 as shown in Fig. 1. Thus, during cycles of operation of the machine with the platen in printing position, the cam 40 has no effect on the position of the platen. But, when the platen is moved to front-feed position, to permit one sheet to be taken out and another inserted, the pass-by pawl 40 40 39 is moved to the position of Fig. 3 where the cam 40 will engage it during the early part of the next machine cycle, to return the platen to printing position for the next operation. The cam is first rocked clockwise and then returned 45 counterclockwise. During the early part of its clockwise movement, it engages the pass-by pawl 39, as shown in Fig. 3. At that time said pawl is held against turning on its pivot by a limit stop, with the result that the lever 37 is rocked clockwise, which, in turn, pulls the arm 25 clockwise 50 to positively rock the platen to printing position. This action occurs prior to operation of the printing mechanism. After the platen has been moved to printing position, it is latched by the 55 latch 34 engaging over the lug 28.

Record sheet

The record or journal sheet J is held about the platen P for a series of operations and is arranged 60 to be line spaced with the platen. The record sheet is shown in Fig. 2 and is inserted from the rear over a paper pan 41 carried by a rod 42 and under the platen and is passed up in front of the platen and turned rearwardly over the platen 65 under rolls 43 carried by arms 44 carried by shaft 45 in the usual manner.

The record sheet is thus held in feeding relation about the platen so that it will be line spaced as the platen is line spaced. Also, as the platen 70 is moved bodily from printing to front-feed posi-

tion and vice versa, the record sheet moves with it without having its line spaced position disturbed. The record sheet is thus always in position to receive copies of the entries that are made on the work sheets which are inserted from time to time, the copies being made by means of carbon paper C which is usually placed around the platen with the record sheet.

Front-feed means

Provision is made for enabling individual work sheets to be inserted from time to time in front of the platen. In order to receive these sheets an opening is preferably provided which will be called the "front-feed throat", the same being arranged to be moved from a closed to an open throat condition and vice versa, as will presently appear. In the embodiment illustrated, the platen P comprises one member of the throat. Cooperating with the platen, and adapted to engage it, are a series of feed or pressure rolls 46 shown most clearly in Fig. 4. These rolls are carried by arms 47 that are fixed to shaft 48 supported in arms 49 secured to the back plate of the machine. Shaft 48 also has secured there- 20 to another arm 51 to which is attached a spring 52 for urging arms 47 and rollers 46 counterclockwise into engagement with the platen. Counterclockwise movement is limited by a hook 53 formed integral with one of the roller arms 47 30 and engaging a stud 54 carried by the upper end of one of the arms 49.

The front-feed throat is opened automatically, in the embodiment shown, at the time the platen is moved from printing position to front-feed position, that is, when it is swung from the position of Fig. 1 to the position of Fig. 3. As the platen swings rearwardly to front-feed position, feed rolls 46 will follow it until limited by hook 53 and as the platen continues in its rearward movement the throat between the platen and the feed rolls is opened to receive a work sheet. When the platen is returned to printing position the parts move in the reverse direction and the front-feed throat is closed.

In order to guide the work sheets to front-fed position a paper table, or chute, 55 (Figs. 1 and 3) is provided which is secured to extensions of the upper ends 57 of the stationary frames 56 attached to the machine back plate. This table remains stationary while the platen moves to and from printing and front-feed position. When the platen is in front-feed position and the throat open, the chute serves as a guide to receive and direct inserted sheets to front-fed position in the open throat. As the platen is returned to printing position, the lower edge of the chute engages the upper end of the inserted sheet above the printing line of the platen and said sheet is thus bent about said platen to hold it in position. The inserted sheet is thus held in printing position on the front-feed side of the platen by being engaged above the printing line of the platen by the edge of the paper chute and by being engaged below the printing line of the platen by the apron 65 or chute on which the stops 60 are mounted. The work sheet is thus bent about the platen and held both above and below the printing line. The pressure rolls 46 also hold said work sheet and cause it to be line spaced when the platen is 70 rotated.

The front-fed work sheets are positioned in proper line space position relative to the printing line of the printing mechanism and the platen when they are dropped in front of the platen, by 75

a series of rearwardly projecting stops 60 formed by bending the upper ends of stationary strips 61 rearwardly which latter strips are secured to a rear paper table or plate 59, and may be formed or adjusted to accommodate them to different sized sheets on which the first line of printing appears in different positions.

Work sheet ejecting means

10 Provision is made for automatically ejecting the work sheets and stacking them in order so that the operator does not need to bother with moving the sheets upon which operations have been performed. The ejecting means comprises 15 a series of resilient strips 62 interspersed between the stationary strips 61 and extending upwardly beyond the stops 60. Means are provided for raising the resilient strips 62 above and beyond the stops 60 so that the work sheets lying upon the stationary strips will be raised clear of stops 60 and allowed to drop downwardly and rearwardly into a receptacle 63.

The resilient strips are actuated to release the work sheets from stops 60 upon opening of the 25 throat, that is, upon movement of the platen from printing position to front-feed position, by means of a cam edge 64 (Figs. 2 and 3) formed on link 36 which edge engages a stud 65 on pass-by pawl 66 carried by an arm 67 secured to a shaft 68. 30 Shaft 68 also rigidly supports a bail 69 which engages down-turned arms 70 formed on each of the resilient strips 62. From the foregoing it will be seen that as link 36 rises from the position of Fig. 2 when the platen is moved rearwardly to 35 front-feed position, the cam edge 64 will engage pass-by pawl 66 and rock shaft 68 clockwise causing its bail 69 to engage arms 70 on strips 62 and forcing the latter upwardly and rearwardly to disengage the work sheets from stops 60. Upon 40 return movement of link 36 pass-by pawl 66 will be ineffective to move shaft 68.

Because link 36 moves and returns rather rapidly, means are provided for latching the ejector strips in raised position. For this purpose shaft 45 68 is provided with an arm 75 to which one end of a link 76 is pivoted, the other end being slidably supported by a stud 77. Intermediate its ends link 76 is provided with a stud 78 adapted to engage and latch the horizontal arm of a bell 50 crank 79 pivoted on stud 77. The vertical arm of bell crank 79 cooperates with the total key mechanism for release, as will later be explained. It follows that as bail 69 and shaft 68 are rocked clockwise stud 78 on link 76 will engage and latch 55 bail 69 and ejector strips 62 in raised or ejecting position until the bell crank 79 is released. When released, the resilience of strips 62 returns them and bail 69 to normal position.

Total key control

60 As previously explained, the ejecting means is automatically operated through power derived from the operating mechanism of the machine and the sheets are positively ejected clear of the 65 positioning stops, but fall into the receptacle by gravity. Control of the ejecting mechanism in the illustrated embodiment is through the total taking key as will now be explained.

70 Total key 13 (Fig. 1) is connected by a link 85 to an arm 86 secured to the key locking shaft 87. Link 85 also carries a stud 88 which when the total key is depressed engages an arm 89 journaled on shaft 87 and connected to an arm 90 carrying a stud 91 normally in position to engage 75 one arm of a two-arm lever 92 pivoted on shaft

92a. The other arm of this two-arm lever, which is retained in counterclockwise position by stud 91, is connected by a link 93 to a hook 94 pivotally connected to latch 31. When the total key is depressed arm 89 is rocked counterclockwise thus 5 removing arm 90 and its stud 91 from the upper arm of the two-arm lever 92 permitting a spring 95 to rock the lever clockwise, thus raising link 93 and moving hook 94 into the path of a lug 96 formed on the outer end of an arm 97 carried by 10 the main shaft 12. With the hook in this position, it will be pulled upon the return movement of lug 96 and upon this return movement will 15 rock latch 31 counterclockwise about its pivot 32 and release hook 34 from lug 28 to permit movement of the platen to front-feed position by spring 29. As the lug 96 continues to move, it automatically releases itself from hook 94 and thereby releases latch 34 for return to normal 20 under the urge of spring 33.

Movement of arm 90 and stud 91 upon depression of the total key also removes the stud from engagement with the vertical arm of bell crank 79 and permits the latter to rotate clockwise and engage stud 78 to retain the resilient strips 62 in 25 raised or ejecting position.

In taking a total, the total key is depressed and the machine given a cycle of operation. The total key is latched down during the major portion of this cycle but is released near the end thereof. 30 When the total key is released, stud 91 on arm 90 returns to its forward position and rocks the two-arm lever counterclockwise to lower hook 94 out of the engaging position with lug 96 and also rocks bell crank 79 counterclockwise to release the 35 resilient strips 62.

It will be seen from the foregoing that, when the machine is conditioned for the function of total taking, certain parts are conditioned so that, during the total-taking cycle, and after the printing mechanism has operated, the front-feed throat will be automatically opened and the work sheet ejected to permit it to drop by gravity into a receptacle. As the totaling operation is completed, 40 the means for arresting a new work sheet in proper position relative to the platen is rendered effective, but the front-feed throat remains open for the receipt of a new work sheet. The operator need only drop a new sheet into position and proceed with the work of entering the next item 50 on the amount keys. He need not pay any attention to the condition of the front-feed throat because, at the beginning of the next machine cycle, the cam 40 engages the pass-by pawl 39 and automatically closes the throat prior to an operation 55 of the printing mechanism.

Single item key control

Machines of this character may be provided with a "single item key" which is used for entering complete transactions involving only the entry of a single amount. Of course in this kind of transaction, it is necessary to clear the machine so that unless a special key is provided it is necessary to enter the single item transaction 65 upon the amount key and then take a total to clear the machine even though a single entry only is in the machine. For this purpose the present machine is provided with a "single item transaction key", a bar 99 which overlaps the 70 motor bar at the upper end.

The ejecting means may also be operated under control of this single item motor bar 99 which is used for printing single item bills, thereby eliminating the necessity of depressing the total key 75

and taking totals on single item bills. For this purpose the single item motor bar 99 (Fig. 1) is connected by link 100 to a shaft 101 to which is also secured an arm 102. Arm 102 carries a stud 103 which projects in front of arm 89 and rocks this arm 89 upon depression of the single item motor bar. This causes stud 91 to leave arm 92 and permits the latter to rock clockwise to raise link 93 and hook 94 to cause automatic ejection 10 as explained in connection with the total key.

Listing spacing of platen

As illustrated on the forms shown in Fig. 6, the platen is given a single line space movement during the listing or entering of items. This movement takes place during the first part of each machine operation and before printing takes place.

The line spacing mechanism is shown most clearly in Fig. 4, from which it will be seen that the platen shaft 20 carries a gear 120 which engages a gear 121 journaled on a stud 122 projecting from the platen frame 21. Gear 121 is rotated for line spacing the platen by means of a pawl 123 pivoted at 124 to the end of a lever 125 pivoted intermediate its ends at 122. Pawl 123 is caused to engage gear 121 by a resilient friction member 126 (Fig. 4) which is pivoted on shaft 122 and whose upper end engages a stud on pawl 123. This friction member is retarded frictionally near 30 its pivot and tends to rotate pawl 123 clockwise about its pivot whenever lever 125 is rotated. Lever 125 has a slotted connection at its lower end with a stud 127 carried by the upper end of a lever 128 pivoted intermediate its ends at 129. Lever 128 carries a roller 130 at its lower end which engages in a cam slot 131 formed in a cam 132 secured to the main shaft 12. During each machine operation cam 132 is rocked counterclockwise during the forward machine stroke, 40 which rocks lever 128 counterclockwise, thus moving lever 125 clockwise and causing the pawl 123 to engage and rotate gear 121 clockwise, which, in turn, rotates gear 120 and platen P counterclockwise.

The arc through which gear 121 is rotated and, accordingly, the line space movement imparted to platen P is determined by a shield 140 which underlies pawl 123 and is carried by the upper end of a lever 141, also pivoted intermediate its 50 ends on stud 122. The lower end of lever 141 has a slotted engagement with stud 142 carried by the upper end of one arm of a crank 143 pivoted at 129. Crank 143 is constantly urged clockwise by a spring 144 and its other arm is formed to provide a laterally projecting lug 145 adapted to engage one arm 146 of a latch pivoted at 147 and having an upwardly extending arm 148. The latch is also constantly urged clockwise by a spring 149 so as to normally engage lug 145.

Latch 146 normally engages lug 145 during all listing or item-entering operations so that shield 140 remains in one position during these operations, the position being such that the pawl 123 60 engages gear 121 at the proper time to rotate platen P a peripheral distance of one line space for each listing operation. In other words, during a forward machine stroke as lever 125 is moved clockwise, pawl 123 slides over the top of shield 140 and drops upon gear 121 and moves 70 the latter sufficiently to impart one line space movement to the platen, after which pawl 123 engages against a fixed stud 150 projecting from frame 21 to limit movement of the pawl and to prevent overthrow of the platen. During 75 return stroke of the machine the parts are re-

stored to their Fig. 4 positions. Cam slot 131 is shaped to cause spacing of the platen just prior to the printing operation which takes place near the end of the forward machine stroke and is formed with a dwell which causes the pawl 123 to be inoperative while printing takes place, i. e., the platen will be stationary when the printing hammers are fired.

Total spacing of platen

Means are also provided for automatically spacing the platen variable distances during a total operation in order to print the total in the same position on each work sheet regardless of the number of items listed on the work sheet. Two samples of such spacing are shown in Fig. 6, which illustrates two samples of work performed by the illustrated embodiment of this invention which is designed to print a total on the seventh line regardless of the number of items printed up to six which make up this total. The section B of this figure illustrates a portion of a bill made up of three items and in which the total is printed on the seventh line. Section C of this figure illustrates a portion of a bill made up of five items and in which the total is printed upon the seventh line. Portion A' of the figure illustrates a copy of the last item and total of a preceding bill which is printed upon a journal strip which, if used, would normally be beneath the bill portion A (not shown). Section B' of the figure illustrates a further portion of the journal strip and likewise section C' illustrates a continuation of the journal strip which would underlie sections B and C in actual application of the machine if a journal strip were used.

The illustrated samples of work make it apparent that regardless of the number of items listed upon a bill the machine automatically line spaces the platen and the bill prior to taking and printing a total, so that the printed total will appear at the seventh line or at the bottom of the bill regardless of the number of items listed which make up the total. An exception occurs, of course, where single items constitute the entire bill. In such instances no total is taken or printed. In such entries the single item motor bar is used, as has been previously explained.

During totaling operations the shield 140 is moved counterclockwise so as to permit pawl 123 to engage the proper number of teeth in gear 121 to cause rotation of the platen through the proper arc prior to total printing, so that the total will always be printed on the seventh line or at the bottom of the bill. The degree of rotation of gear 121 and of the platen necessary to cause the total to be printed at the bottom of the bill will, of course, vary according to the number of items listed which make up the total. Accordingly, shield 140 must be rotated counterclockwise varying amounts, as determined by the number of listed items. The mechanism for accomplishing this will now be described.

As was previously explained, when the total key 13 is depressed shaft 87 is rocked. This shaft extends across the machine and upon its left end 65 carries an arm 151 (Figs. 4 and 5). Arm 151 carries a stud 152 upon its lower end which engages the upper arm 148 of latch 146 when shaft 87 is rocked by depression of the total key. This releases the latch from lug 145 and permits crank 70 143 to be rotated clockwise about its pivot by a spring 144, thereby rotating lever 141 counterclockwise and moving shield 140 rearward. This release occurs prior to movement of the platen caused by rocking of arm 89 also controlled by 75

the total key. The amount of movement of crank 143 and shield 140 is controlled by an index plate 160 pivoted at 147 and urged counterclockwise by a spring 161. The index plate 160 is provided with a series of notches or steps 162 which steps are engaged by lug 145 of crank 143 and limit the clockwise rotation of the latter to determine the movement of lever 141 and shield 140. Movement of index plate 160 is controlled by engagement of a stud 163 carried by a lower arm of the index plate with steps 164 formed on the periphery of a cam plate 165 pivoted on shaft 129 and urged clockwise by a spring 166.

Cam 165 is moved a step at a time at each machine operation by means of a pawl 167 pivoted at 168 to the lower end of lever 128 which, it will be recalled, is rocked at each machine operation. Pawl 167 engages teeth 169 cut into the periphery of cam 165 and substantially diametrically opposite to steps 164. Cam 165 is retained in its new positions to which it is moved by pawl 167 by a detent 170 pivoted at 171 to the frame of the machine and having a lug 172 adapted to engage the teeth 169 of the cam, the detent being normally urged clockwise by the springs 144 and 161, both of which are attached to the detent. Accordingly, at each machine operation cam 165 is moved one step counterclockwise and is retained at each step of movement by detent 170. Index plate 160 is also moved step by step, corresponding to the movements of cam 165 and corresponding to each machine operation by engagement of stud 163 with the notched edge 164 of the cam.

As illustrated in Fig. 5, cam 165 has been advanced three steps, because of the three listed items, and the index plate 160 has been indexed counterclockwise from the Fig. 4 position to the Fig. 5 position to limit the movement of crank 143 and the movement of pawl 123 if latch 146 has released lug 145 and crank 143 by depression of the total key. In other words, if the total key were depressed lever 151 is moved clockwise from the full line position of Fig. 4 to the full line position of Fig. 5, and latch 146 releases crank 143 and the latter moves to the Fig. 5 position. This permits movement of shield 140 a corresponding distance to permit pawl 123 to engage gear 121 at the proper tooth to rotate the platen to the seventh line position.

For example, if three items are listed on the bill as illustrated in section B of Fig. 6, the cam 165 is moved three steps counterclockwise, which moves the shield 140 sufficiently rearward to enable pawl 123 to move the platen a distance equal to the remaining four line spaces to the seventh line position during the forward stroke of the machine in a totaling operation, and in time to cause the total to be printed at the bottom of the bill or in the seventh line. On the other hand, if the number of listed items is five, as shown in section C of Fig. 6, cam 165 will be moved five steps counterclockwise and this will raise the index plate 160 so that the shield 140 will be moved sufficiently rearward to enable the pawl 123 to move the platen a distance equal to the remaining two line spaces, causing the total again to be printed in the seventh line or at the bottom of the bill. It will be apparent to those skilled in the art that providing six lines for item printing and printing the total in the seventh line is merely one embodiment of the invention and other spacings may be provided for as desired by proper design of cam 165 and index plate 160.

After spacing of the platen for total printing cam 165 must of course be returned to normal

position. For this purpose the throwback cam 25 at the left side of the machine (Figs. 4 and 5), which moves in a clockwise direction from the Fig. 5 position, is provided with a forwardly extending arm 175 which engages a stud 176 projecting from an extension of crank 143 and rocks the latter counterclockwise and moves its lug 145 away from latch 146. Arm 175 of cam 25 is provided with a stud 177 which engages a rearwardly projecting finger 178 of detent 170 and releases the latter from the teeth 169 of cam 165. From the foregoing it will be seen that the left cam 25 when rocked clockwise (Fig. 5) to cause an opening of the platen following printing of a total, causes a release of latch 146 and detent 170, thereby permitting restoration of index plate 160 and cam 165. The spacing mechanism is then reconditioned for single line spacing movements with lug 145 reengaged by latch 146.

After the totaling operation has been completed and the work sheet ejected from the carriage, a new work sheet is inserted in the carriage and the amount of the first item indexed on the keyboard. After this the motor bar is depressed for the first item-printing operation, which causes cam 40 (Fig. 1) to move the platen to printing position, which movement is completed just prior to engagement of pawl 123 with gear 121 to line space the platen one line before the item is printed. This means that the first item following the total printing operation is printed one line space below the total on both the work sheet or bill and the journal sheet, if the latter is used. It will be apparent that in the present machine platen spacing movements are accomplished during the forward machine stroke and before printing occurs in both listing and totaling operations.

Operation

Although the operation of the machine should be clear from the foregoing description, a brief summary thereof will be given.

First a record sheet is inserted about the platen, which can readily be done because the platen normally is in throwback position. After the record sheet is threaded under the platen from the rear a work sheet is dropped into the front-feed throat over table 55, the sheet limiting against the stop 60.

The necessary keys are depressed for the first entry and the motor bar is depressed to give the machine a cycle of operation. Upon depression of the motor bar the driving shaft 12 is moved clockwise (Fig. 1) and the cam 40 engages pass-by pawl 39 and rocks lever 31 and arm 25 of the bell crank to move the platen to printing position just prior to engagement of pawl 123 with gear 121 to line space the platen and in time to receive the first printed amount of the transaction. That is, the work sheet is grasped upon the automatic closing of the front-feed throat and the upper end of the sheet is moved to position for receiving the entry. The platen remains latched in printing position and the front-feed throat in closed position during the entry of further items.

When the last entry has been made and it is desired to take and print a total, the total key 13 is depressed. This causes rotation of shaft 87 and automatic positioning of the shield 140. As the machine is cycled, and before printing occurs, the platen is line spaced the necessary number of lines to cause the total to be printed in the seventh line when printing occurs near the end of the forward stroke of the machine. Depression of the total key also releases the lever 92.

whereupon the hook 94 is moved into the path of lug 96 on the arm 97 on the main drive shaft 12. Upon counterclockwise movement of the main shaft during the early portion of the return stroke, and after operation of the printing mechanism, lug 96 engages hook 94 and releases the latch for link 36. The link thereupon moves upward, moves the platen to front-feed position, opens the front-feed throat, and causes the resilient strips 62 to move to ejecting position to move the work sheet over stop 60 so that said sheet may move down into the receptacle 63.

Depression of the total key also releases the latch 78 (Fig. 3) so that, after the resilient ejecting strips are moved to ejecting position, they will be temporarily held in said position.

As the main shaft continues in its return stroke, the lug 96 automatically releases itself from hook 94, whereupon the latch 34 for the platen moves back to normal so as to be ready to latch the platen in printing position when said platen is returned to printing position. As the platen moved to front-feed position as above described, the lever 37 (Fig. 1) moved counterclockwise so that pawl 39 is in the path of cam 40, but, because of the arrangement of pass-by pawl 39, said cam has no effective action on lever 37 during the return stroke.

Near the end of the machine cycle, the total key is released, whereupon it returns to normal. This causes the latch 79 to be released, whereupon the resilient ejecting strips return to normal, thereby rendering the stop 60 effective to arrest the next sheet. The restoration of the total key also causes the hook 94 to be disabled.

At the end of the cycle, the platen is in front-feed position, the front-feed throat is open, and the stop 60 is effective.

The operator can then insert a new sheet, 40 press the amount keys, and then depress the motor bar. As the machine starts to cycle, the cam 40 (Fig. 1) engages pawl 39 and rocks lever 37 clockwise to pull the platen to printing position and to close the front-feed throat, the parts being latched in said position by the latch 34.

In other words, when the operator depresses the total key and gives the machine a cycle of operation, the platen is automatically line spaced the required distance to print the total in the seventh line; the total is printed; the platen is thrown back and the front-feed throat opened; the ejecting means operates to eject the sheet; and at the end of the cycle the throat is left open, the stop for arresting a new sheet effective, and the machine in condition to automatically close the throat at the beginning of the next cycle.

If the entry has been a single item transaction instead of multiple items and if the single item key or bar was used, depression of this single item transaction key or bar will cause the machine to operate in the manner just described for the total key.

As will be understood, the operation is wholly automatic. All the operator need do is place the successive work sheets in position, enter the amounts on the keyboard, depress the motor bar and, when necessary, depress the total key.

It will be understood that the construction shown is for purpose of illustration only and that variations may be made in it without departing from the spirit and scope of the invention as defined by the appended claims.

I claim:

1. A front-feed machine of the class described having a printing means normally operating at

a predetermined time during a machine operation, a platen, front-feed means for enabling a work sheet to be front fed relative to said platen, said front-feed means including portions forming a throat that is movable from a closed to an open-throat condition and vice versa, said throat being urged to open condition, means for closing said throat, a latching means for maintaining said throat in closed condition, means for conditioning said machine to perform a predetermined function, and means operating automatically, when said machine is conditioned by said function conditioning means and operated, to cause said throat to be opened after said printing means has operated during the operation of the machine.

2. A front-feed machine of the class described having a printing means normally operating at a predetermined time during a machine operation, a platen, front-feed means for enabling a work sheet to be front fed relative to said platen, said front-feed means including portions forming a throat that is movable from a closed to an open-throat condition and vice versa, said throat being urged to open condition, means for closing said throat, a latching means for maintaining said throat in closed condition, and means conditionable by the manipulation of a single member for rendering said latching means ineffective and for causing said throat-opening means to automatically open the throat after an operation of the printing means, whereby, when said manipulative member is manipulated and the machine operated, the throat will be opened.

3. A front-feed machine of the class described having a printing means normally operating at a predetermined time during a machine operation, a platen, front-feed means for enabling a work sheet to be front fed relative to said platen, said front-feed means including portions forming a throat that is movable from a closed to an open-throat condition and vice versa, said throat being urged to open condition, a latching means for latching said throat in closed condition, total taking control means, and means governed by said total taking control means for rendering said latching means ineffective and for causing said throat to be automatically opened after the printing means has operated during a total taking operation.

4. In a calculating machine adapted to accumulate items and to be conditioned to perform various functions, a printing means, a platen, means for holding a work sheet in printing position relative to said platen, means normally operating to line space said work sheet a predetermined amount for each item entering operation, means for conditioning said machine for a predetermined function, and means operating automatically, when said machine is conditioned by said function conditioning means and operated, to cause said line spacing means to move said work sheet to a special predetermined position irrespective of the number of item line spacing movements that have preceded it in the series of items that is entered.

5. In a calculating machine adapted to accumulate items and to take and print the totals thereof, printing means, a platen, means for holding a work sheet in printing position relative to said platen, means normally operating to line space said work sheet a predetermined distance for each item entering operation, total taking control means for conditioning the machine for total taking, and means operating automatically,

when said machine is conditioned for total taking and operated, to control the degree of movement of said line spacing means to line space said work sheet to a predetermined position to thereby cause the total to be printed in the same place on each work sheet irrespective of the number of items in the series of items whose total is taken.

6. A calculating machine of the class described capable of listing amounts and accumulating and printing totals thereof, and having amount keys, a printing means, a total key for controlling total taking and printing operations, a rotatable platen, sheet holding means for positioning a work sheet in printing position relative to said platen while the sheet receives printing impressions from said printing means along the printing line, a pawl for line spacing said platen, means for operating said pawl to cause line spacing of the platen at each machine operation, and means controlled by said total key for varying the effect of said pawl to cause said platen to be rotated to a predetermined position prior to printing a total, said latter means also being controlled in accordance with the line space position of said platen prior to total taking.

7. A calculating machine of the class described capable of listing amounts and accumulating and printing totals thereof, and having amount keys, a printing means, a total key for controlling total taking and printing operations, a rotatable platen, sheet holding means for positioning a work sheet in printing position relative to said platen while the sheet receives printing impressions from said printing means along the printing line, means for line spacing said platen, means for operating said line spacing means to cause line spacing of the platen at each machine operation, and means controlled by said total key for actuating said line spacing means to rotate said platen to a predetermined position prior to printing a total, said latter means also being controlled in accordance with the line space position of said platen prior to total taking.

8. A calculating machine of the class described capable of listing amounts and accumulating and printing totals thereof, and having amount keys, a printing means, a total key for controlling total taking operations, a rotatable platen movable bodily from a printing position relative to said printing means to an out-of-printing position and vice versa, sheet holding means for positioning a work sheet in printing position relative to said platen while it receives printing impressions from said printing means along the printing line, means controlled by said total key for moving said platen from one position to the other, means for line spacing said platen, means for operating said line spacing means to cause line spacing of said platen at each machine operation, and means controlled by said total key and operable prior to bodily movement of said platen for causing rotation of said platen to a predetermined position prior to printing a total, said latter means also being controlled in accordance with the line space position of said platen prior to total taking.

9. A calculating machine of the class described capable of listing amounts and accumulating and printing totals thereof, and having amount keys, a printing means, a total key for controlling total taking operations, a rotatable platen movable bodily from a printing position relative to said printing means to an out-of-printing position and vice versa, sheet holding means for positioning a work sheet in printing position relative to said platen while it receives printing impressions

from said printing means along the printing line, means controlled by said total key for moving said platen from one position to the other, means for line spacing said platen, means for operating said line spacing means to cause line spacing of said platen at each machine operation, means controlled by said total key and operable prior to bodily movement of said platen for causing rotation of said platen to a predetermined position prior to printing a total, and means for controlling the degree of movement of said latter means in accordance with the number of amounts listed prior to total taking.

10. In a calculating machine adapted to accumulate items and to take and print the totals thereof, printing means, a platen, front-feed means for enabling a work sheet to be front fed relative to said platen and for holding said sheet in front-fed position for operations of said printing means, said front-feed means including portions forming a front-feed throat movable from a closed to an open-throat condition and vice versa, means normally operating to line space said work sheet a predetermined distance for each item entering operation, total taking means for conditioning the machine for total taking, means governed by said total taking conditioning means operating automatically, when said machine is conditioned for total taking and operated, to line space said work sheet to a predetermined position to thereby cause the total to be printed in the same place on each work sheet irrespective of the number of items that have been entered in the series of items whose total is taken, and, after the total is printed, to open said throat, and a single item means operable to condition said machine for an operation in which said throat is opened without line spacing said work sheet.

11. A front-feed machine of the class described having a printing means, a platen, front-feed means for enabling a work sheet to be front fed relative to said platen and for holding said sheet in front-fed position for an operation of said printing means, said front-feed means including portions forming a throat that is movable from a closed to an open-throat condition and vice versa, sheet arresting means operable, when a sheet is inserted in said throat while it is open, to arrest said sheet in a predetermined position relative to said platen, means for closing said throat, and means operable to open said throat, to render said arresting means ineffective to arrest said sheet to thereby enable said sheet to move out of said throat past said arresting means, and to thereafter cause said arresting means to be again rendered effective to arrest a new sheet that may be inserted in said open throat.

12. A front-feed machine of the class described having a printing means, a platen, front-feed means for enabling a work sheet to be front fed relative to said platen and for holding said sheet in front-fed position for operation of said printing means, said front-feed means including portions forming a throat that is movable from a closed to an open-throat condition and vice versa, means operable, when a sheet is inserted to a substantially vertical position in said throat while it is open, to support said sheet in a predetermined position relative to said platen, means for closing said throat to grip said inserted sheet for a printing operation, and means operable to open said throat to release said sheet, to render said supporting means ineffective to support said sheet to thereby enable the sheet to drop out of said

throat, and to thereafter cause said supporting means to be again rendered effective to support a new sheet.

13. A front-feed machine of the class described having a printing means, a platen, front-feed means for guiding a work sheet into a substantially vertical position on the front-feed side of said platen, said front-feed means including portions forming a front-feed throat that may be moved from closed to open-throat condition and vice versa, sheet-supporting means for arresting an inserted work sheet in proper line space position relative to said printing means when said sheet is inserted into said open throat and for supporting said sheet in substantially vertical position in said open throat, means for closing said throat to cause said front-feed means to grip said inserted sheet prior to an operation of said printing means, means for subsequently opening said throat, sheet ejecting means for moving said inserted work sheet relative to said supporting means, and means operating automatically, as said front-feed means is moved to open-throat condition, to cause said ejecting means to move said sheet clear of said supporting means to enable said sheet to drop out of said open throat and away from said platen by gravity.

14. A front-feed machine of the class described having printing means, a platen, means for guiding a work sheet into a substantially vertical position on the front-feed side of said platen, means for engaging a front-fed work sheet above and below the printing line of said platen to hold said sheet about said platen for a printing operation of said printing means, said platen and said sheet engaging means being mounted to enable a relative movement to occur between them to hold said sheet while printing occurs and to subsequently release said sheet for removal, sheet-supporting means for arresting said front-fed sheet in proper line space position when it is guided to front-fed position and for supporting it in said position when not engaged by said engaging means, and sheet ejecting means operating automatically, when a relative movement is caused between said platen and sheet engaging means to release said sheet, for moving said sheet relative to its supporting means to thereby free said sheet to enable it to move away from said platen by gravity.

15. A front-feed machine of the class described having a printing means, a platen movable from a printing position relative to said printing means to a front-feed position and vice versa, front-feed means for enabling a work sheet to be front fed relative to said platen, said front-feed means including portions forming a throat that is movable from a closed to an open-throat condition and vice versa, sheet arresting means operable, when a sheet is inserted in said throat while it is open, to arrest said sheet in a predetermined position relative to said platen, means for moving said platen to printing position and closing said throat, and means operable to move said platen to front-feed position, to open said throat, to render said arresting means ineffective to arrest said sheet to thereby enable said sheet to move out of said throat past said arresting means, and to thereafter cause said arresting means to again be effective to arrest a new sheet that may be inserted in said open throat.

16. A front-feed machine of the class described having a printing means, a platen movable bodily from a printing position relative to said printing means to an out-of-printing position and vice

versa, means for moving said platen from one position to the other, means for guiding a work sheet into a substantially vertical position in front of said platen, sheet supporting means for arresting said inserted work sheet in proper line space position relative to said printing means and for supporting said sheet in said position while said platen is out of printing position, sheet-engaging means for holding said sheet in position for a printing operation when said platen is moved to printing position and for subsequently releasing it, and means operating automatically, as said sheet is released, for moving said sheet relative to said supporting means to thereby free it to enable it to drop by gravity away from said platen.

17. A front-feed machine of the class described having printing means, a platen, means for holding a record sheet about said platen, front-feed means for enabling a work sheet to be front fed to a substantially vertical position relative to said platen, said front-feed means including portions forming a front-feed throat movable from an open to a closed-throat condition and vice versa, sheet-supporting means for arresting said sheet in proper line-space position relative to said printing means and for supporting it in said position while said throat is open, a work sheet ejecting means normally tending to move said sheet clear of said supporting means but latched against such movement, power-actuated means operable to control the opening of said front-feed throat and the release of said ejecting means whereby said work sheet is moved clear of said supporting means to enable it to drop out of said throat and away from said platen while leaving the record sheet about said platen, and power operated means for closing said throat and conditioning said throat-opening and ejecting means for subsequent operation.

18. A front-feed machine of the class described having means for giving it cycles of operation, printing means, a platen, means for holding a record sheet about said platen, front-feed means for enabling a work sheet to be front fed to a substantially vertical position relative to said platen, said front-feed means including portions forming a front-feed throat movable from an open to a closed-throat condition and vice versa, sheet-supporting means for arresting and supporting an inserted sheet in proper line-space position relative to said printing means while said throat is open, work sheet ejecting means for moving said work sheet relative to said supporting means, and power means operating automatically during a machine cycle to open said throat and to cause said ejecting means to move said work sheet free of said supporting means to thereby enable said sheet to fall clear of said platen while said record sheet remains about said platen.

19. A front-feed machine of the class described having means for giving it cycles of operation, printing means operated at a predetermined time during a machine cycle, a platen, means for holding a record sheet about said platen, front-feed means for enabling a work sheet to be front fed to a substantially vertical position relative to said platen, said front-feed means including portions forming a throat that is movable from an open to a closed-throat condition and vice versa, sheet-supporting means for arresting the front-fed work sheet in proper line-space position relative to said platen and for supporting said sheet in said position while said throat is

- open, work sheet ejecting means for moving said work sheet relative to said supporting means, and power means operating automatically during a cycle of machine operation to close said throat, to grip an inserted work sheet prior to operation of said printing means and to subsequently operate, after said printing means has operated, to cause said throat to be opened and said ejecting means to move said work sheet clear of said supporting means whereby said sheet may drop out of said open throat and clear of said platen while said record sheet remains about said platen.
20. A front-feed machine of the class described having a printing means, a platen, front-feed means for enabling a work sheet to be front fed relative to said platen and for holding said sheet in front-fed position for printing operations, said front-feed means including portions forming a throat that is movable from a closed to an open-throat condition and vice versa, a normally inactive sheet-ejecting means, a manipulative member for conditioning said machine for a predetermined type of operation, means for opening said throat, and means governed by said manipulative member for rendering said ejecting means active when said throat is opened whereby said sheet will be automatically ejected when said throat is opened during said predetermined type 30 of operation of said machine.
21. A front-feed machine of the class described having a printing means, a platen, front-feed means for enabling a work sheet to be front fed relative to said platen and for holding said sheet in front-fed position for printing operations, said front-feed means including portions forming a throat that is movable from a closed to an open-throat condition and vice versa, a normally inactive sheet-ejecting means, functioning conditioning means for conditioning said machine for a predetermined function, means for opening said throat, and means governed by said functioning conditioning means for rendering said ejecting means active when said throat is opened to thereby cause said sheet to be ejected when said throat is opened after said machine is operated to perform the function determined by said functioning conditioning means.
22. A front-feed machine of the class described having a printing means, a platen, front-feed means for enabling a work sheet to be front fed relative to said platen and for holding said sheet in front-fed position for printing operations, said front-feed means including portions forming a throat that is movable from a closed to an open-throat condition and vice versa, normally inactive sheet-ejecting means, normally inactive means for opening said throat, and total taking means operable to render said ejecting means effective and to condition said throat opening means for operation whereby, during a total taking operation, said throat will be opened after operation of said printing means and the work sheet automatically ejected.
23. A front-feed machine of the class described having means for giving the cycles of operation, function keys for conditioning said machine for different functions, printing means, a platen, means for holding a record sheet about said platen, front-feed means for enabling a work sheet to be front-fed to a substantially vertical position relative to said platen, said front-feed means including portions movable from an open to a closed-throat condition and vice versa, sheet-supporting means for arresting said front- 75
- fed work sheet in proper line-space position relative to said printing mechanism and for supporting said sheet in said position while said throat is open, work sheet ejecting means for moving said sheet relative to said supporting means, power means operable automatically during a cycle of machine operation to open said throat and cause said ejecting means to move said work sheet relative to said supporting means to enable said sheet to fall out of said open throat and clear of said platen, and connections from one of said function keys for controlling said power means to thereby selectively choose the cycle during which said ejecting operation shall take place.
24. A front-feed machine of the class described having a printing means, a platen, front-feed means for enabling a work sheet to be front fed relative to said platen and for holding said sheet in front-fed position for printing operations, said front-feed means including portions forming a throat that is movable from a closed to an open-throat condition and vice versa, normally inactive sheet-ejecting means, normally inactive means for opening said throat, total taking means operable to render said ejecting means effective and to condition said throat opening means for operation whereby during a total taking operation said throat will be opened after operation of said printing means and the work sheet automatically ejected, and a single item control means operable to cause said throat to be opened and the work sheet automatically ejected after the entry of a single item in said machine.
25. A front-feed machine of the class described having a printing means, a platen, front-feed means for enabling a work sheet to be front fed relative to said platen and for holding said sheet in front-fed position for printing operations, said front-feed means including portions forming a throat that is movable from a closed to an open-throat condition and vice versa, said throat being urged to open condition, latching means for holding the throat in closed condition, a normally inactive means for releasing said latching means, a normally inactive sheet-ejecting means, total taking means operable to render said ejecting means active and to condition certain elements of said machine to cause said latching means to be released after the printing means has operated during a total taking operation whereby the throat will be opened and the work sheet automatically ejected, and a normally inactive throat closing means movable, when the throat is opened, to a position such that it will be operated during the succeeding machine cycle to close said throat.
26. A front-feed machine of the class described having a printing means, a platen movable from a printing position relative to said printing means to a front-feed position and vice versa, feed rolls cooperating with said platen to form a front-feed throat, said feed rolls being movable bodily with said platen, and said platen and feed rolls being relatively movable to open and close said throat, said platen being urged to front-feed position and said throat to open position, latching means for holding said platen in printing position and said throat in closed condition, a normally inactive means for releasing said latching means, a normally inactive sheet-ejecting means, total taking means operable to render said sheet-ejecting means active and to condition certain elements of said machine to cause said latching 75

means to be released after the printing means has operated during a total-taking operation to thereby release said platen for movement to front-feed position and said throat to open position, and normally inactive means for moving said platen to printing position and said throat to closed condition, which means is moved, when

said platen is moved to front-feed position to a position such that, during the succeeding machine cycle, the platen will be returned to printing position and the throat closed prior to operation of the printing means.

ROBERT L. MULLER.
